(57) **CLAIM**

The ornamental design for a garden telescopic hose, as shown and described.

DESCRIPTION

FIG. 1 is a perspective view of a garden telescopic hose showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is another perspective view in stretched condition thereof.

The garden telescopic hose is shown with a symbolic break in its length in FIGS. 1-5 and 8. The appearance of any portion of the article between the break lines forms no part of the claim.

The broken lines throughout the drawing figures depict portions of the Garden telescopic hose that form no part of the claimed design.
